UNITED STATES PATENT OFFICE.

HARRY A. HOLMES, OF AURELIA, IOWA.

PUNCHING MACHINE.

Application filed July 8, 1922. Serial No. 573,573.

To all whom it may concern:

Be it known that I, HARRY A. HOLMES, a citizen of the United States, residing at Aurelia, in the county of Cherokee and State 5 of Iowa, have invented new and useful Improvements in Punching Machines, of which the following is a specification.

This invention relates to punching machines and has for its object the provision 10 of a machine carrying or embodying a plurality of selectively usable dies and punches co-operating therewith, means being provided whereby any selected punch may be engaged by an operating plunger.

15 An important object is the provision of a device of this character in which the punches and dies are always in line ready for use without adjustment.

Still another object is the provision of a 20 device of this character in which the proper dies are always in association with the proper punches, selection of the desired punch and die being accomplished by rotary movement of the die and punch carrier.

25 Still another object is the provision of a machine of this character which is provided with novel lever operating means for actuating the plunger so that great power may be exerted for punching metal sheets 30 of any gauge.

An additional object is the provision of a device of this character which will be comparatively simple and easy to manufacture, simple to operate, efficient and durable in 35 service and a general improvement in the art.

With the above and other objects and advantages in view the invention consists in the details of construction to be hereinafter 40 more fully described and claimed and illustrated in the accompanying drawings, in which:

Figure 1 is a side elevation of the device,

45 Figure 2 is an elevation taken at right angles to Figure 1,

Figure 3 is a longitudinal vertical section showing one of the punches as moved downwardly,

Figure 4 is a horizontal section looking 50 down upon the die carrier,

Figure 5 is a horizontal section looking down upon the punch carrier,

Figure 6 is a detail elevation of the track.

55 Figure 7 is a detail elevation looking at the edge of the plunger and showing the manner of shifting the punches,

Figure 8 is a detail perspective view of one of the dies,

Figure 9 is a detail perspective view of one of the punches.

Referring more particularly to the drawings the numeral 10 designates the base of the machine from which rises a U-shaped frame 11 within the open portion of which is mounted the punching mechanism to be 65 described. The lower arm 12 of the frame is bifurcated and mounted within the bifurcation is a bearing 13 within which is rotatable a vertical shaft 14 upon which is keyed or otherwise secured the die carrier designated broadly by the numeral 15.

The die carrier is formed as a disk 16 provided with a plurality of holes 17 within which are detachably engaged the dies 18 which are held in place by set screws 19 or 75 the like. The dies are here shown as formed with flanges 20 which engage the top of the disk and operate to prevent the dies from slipping down out of place.

The upper end of the shaft 14 is journaled 80 in a bearing 21 on a bracket 22 which is secured against the inside of the vertical portion of the frame 11 and located below this bracket is an interrupted circular track 23 supported by an arm 24 secured thereto 85 and to the bracket 22, and furthermore supported by a pair of brackets or arms 25 which are secured to the upper arm 26 of the frame and to the track at the sides of the opening 27 therein.

90 The track 23 is formed of two sections 23^a and 23^b which have their meeting ends preferably extending diagonally as shown. Riveted upon the underside of the section 23^b is a plate member 23^c which underlaps 95 the section 23^a and which is bolted thereto by means of a bolt 23^d.

Keyed upon the shaft 14 is the punch carrier which consists of a disk 28 formed with openings 29 through which are slidably 100 mounted punches 30 located above and co-operating with the corresponding dies 18. At their upper ends these punches are formed with reduced necks 31 and heads 32. The punches are supported in inactive position by the engagement of these heads upon the track 23.

Slidable through the upper arm of the frame is a plunger 33 which has its lower end carrying jaws 34 adapted to engage the 110 punches for effecting operation thereof.

Each end of the upper arm of the frame

carries an extension, one being designated by the numeral 35 and the other by the numeral 36. Pivoted upon the extension 35 is a lever 37 which is pivotally connected with the upper end of the plunger 33 by links 38 and this lever has its free end pivotally connected by links 39 with the operating lever 40 which is pivoted upon the extension 36. The numeral 41 designates a stop member 10 which is hinged upon the top of the upper arm of the frame and which is engageable beneath the lever 37 for holding all the parts in inactive position.

The operation is as follows: The operator 15 rotates the punch carrying disk and the die carrying disk 16 and 28 together as a unit to bring the desired punch below the plunger 33. When the punch carrier is rotated the punches are of course carried around with 20 it and the heads 32 thereof ride on the track 23. The jaws 34 carried by the plunger substantially fill the opening 27 in the interrupted track so that the heads of the punches will ride over these jaws when passing the 25 interruption in the track. Rotation is continued until the desired punch has its head disposed between the jaws of the plunger. The material to be punched is then laid over the corresponding die 18 and the operator 30 then grasps the lever 40 and presses it down which will result in downward movement of the plunger. As the plunger moves down, the lower and thereof will engage the top of the head of the selected punch and force the 35 punch down into co-acting relation to the associating die. When the lever is subsequently moved upwardly the punch carrier may be rotated to bring a different punch into active position but it is to be noted that 40 such cannot of course occur until the plunger is elevated to the point where the jaws constitute means for filling the interruption in the trackway.

A distinct feature of advantage is that in 45 case a punch becomes broken or needs to be replaced or any other reason bolt 23^a may be removed to effect removal of the track section 23^b so that the punch may be easily taken out without interfering with any of 50 the other parts of the mechanism.

From the foregoing description and a study of the drawings it will be apparent that I have thus provided a simply constructed and consequently inexpensive punching machine which is quickly and easily adjustable or shiftable to permit use of any selected one of a large number of punches. It is likewise to be observed that the punches and dies are always in alignment so that there 55 will be no possibility of improper action. It is of course apparent that the device will be a great time and labor saver so as to be a manifest improvement over the ordinary machines of this type. Owing to the simplicity of the construction and the fewness

of the parts it will be apparent that there is very little to get out of order so that the device should have a long life and satisfactorily perform all of its functions.

While I have shown and described the 70 preferred embodiment of the invention it is of course to be understood that I reserve the right to make such changes in the form, construction and arrangement of parts as will not depart from the spirit of the invention or the scope of the subjoined claims. 75

Having thus described my invention I claim:

1. A machine of the character described comprising a base, a frame mounted thereon, a vertical shaft journaled in the frame, a die carrier rotatably mounted on the shaft, a punch carrier rotatably mounted upon the shaft above the die carrier, dies carried by the die carrier, punches carried by the punch carrier, a stationary track mounted above the punch carrier and supporting the punches in normally elevated position, said track being provided with an opening, and a lever actuated plunger movably mounted in the frame and adapted to be projected through the opening in the track, said plunger carrying means engageable with a selected punch. 80 85 90

2. A machine of the character described comprising a base, a U-shaped frame mounted thereon, a vertical shaft journaled in the lower arm of the frame and projecting into the open space therein, a die carrier secured upon said shaft and carrying a plurality of dies, a punch carrier secured upon said shaft and carrying a plurality of slidably mounted punches located above the corresponding dies, a vertically movable plunger adapted to engage a selected punch, 100 105 and lever means for moving the plunger, a stationarily mounted interrupted track member of circular form mounted above the punch carrier, all of the punches being formed with reduced necks terminating in 110 heads riding upon said track member, and jaws at the lower end of the plunger constituting means for filling the interrupted portion of the track. 115

3. A punch machine comprising a base, a U-shaped frame thereon, a shaft journaled in the lower arm of the frame and projecting vertically, a die carrier formed as a disk secured upon said shaft and having a plurality of openings having dies seated therein, a punch carrier formed as a disk secured upon the shaft in spaced relation to the dies and formed with a series of vertical holes, punches slidable through said holes and co-operating with the associated dies, a 120 125 track member stationarily mounted above the punch carrier, said punches being formed with heads riding upon said track member when the punch and die carrier are rotated, a lever operated plunger slid- 130

able through the upper arm of the frame and provided at its lower end with jaws, and said track member being formed with an interrupted portion for the accommodation of said plunger and the jaws thereof, said jaws constituting a completion of the track when the plunger is in elevated position.

4. A machine of the character described comprising a base, a frame secured thereon and including upper and lower arms, a die carrier rotatable above the lower arm of the frame and carrying a plurality of detachably mounted dies, a punch carrier above and rotatable with the die carrier, a stationary track mounted above the punch carrier, said track being interrupted at a point, punches slidable through the punch carrier and adapted to co-operate with the associated dies, said punches normally engaging said track member and being held thereby in inoperative position, and a lever operated plunger for forcing downwardly which ever punch is disposed within said interrupted portion, the lower end of the plunger carrying means for subsequently lifting the down pressed punch to normal position.

5. A machine of the character described comprising a base, a frame mounted thereon, a die carrier rotatable in the frame and carrying a plurality of dies, a punch carrier above and rotatable with the die carrier, a stationary track above the punch carrier having an opening, punches slidable through the punch carrier and adapted to co-operate with the associated dies, said

punches normally engaging the track member and being held thereby in inoperative position, and a plunger for forcing downwardly which ever punch is desired within said opening, the plunger carrying means for engaging and supporting a punch.

6. A machine of the character described comprising a support, a die carrier rotatable thereon and carrying a plurality of dies, a punch carrier above and rotatable with the die carrier, a stationary interrupted track above the punch carrier, a plurality of punches slidable through the punch carrier and co-operating with the associated dies, said punches being normally supported by said track in inoperative position, and means for engaging and forcing downwardly a punch at the interrupted portion of the track.

7. A machine of the character described comprising a support, a die carrier rotatable thereon and carrying a plurality of dies, a punch carrier above and rotatable with the die carrier, a stationary interrupted track above the punch carrier, a plurality of punches slidable through the punch carrier and co-operating with the associated dies, said punches being normally supported by said track in inoperative position, means for engaging and forcing downwardly a punch at the interrupted portion of the track, said means filling said interruption when in inactive position whereby the track will be continuous.

In testimony wherof I affix my signature.

HARRY A. HOLMES.
